UNITED STATES PATENT OFFICE.

WILLIAM M. MACKAY, OF NEWARK, NEW JERSEY.

STEAM AND HOT-WATER BOILER FORMED OF CIRCULAR SECTIONS.

No. 881,137.

Specification of Letters Patent. Patented March 10, 1908.

Application filed April 12, 1907. Serial No. 367,841.

To all whom it may concern:

Be it known that I, WILLIAM M. MACKAY, a citizen of the United States, residing at 66 James street, Newark, county of Essex, and 5 State of New Jersey, have invented certain new and useful Improvements in Steam and Hot-Water Boilers Formed of Circular Sections, fully described and represented in the following specification and the accompanying drawings, forming a part of the same.

The present invention relates to a boiler formed of horizontal cast iron sections of circular form having each a central hub for a water connection, so that the water circulates upward and downward through the 15 series of superposed hubs.

The invention embraces a particular construction for the firebox section and for the superposed sections, and for the connections 20 to a damper regulator, and the construction will be understood by reference to the annexed drawing, in which

Figure 1 is a front elevation of the complete boiler; Fig. 2 is a plan of the section 25 next below the dome section, with the cleaning-out door and smoke-outlet which are applied to the space between the sections; Fig. 3 is a plan of a disk-section; Fig. 4 is a vertical section where hatched on line 4—4 in Fig. 30 2; Fig. 5 shows the top of the firebox section; Fig. 6 is a section on line 6—6 through the firebox section; Fig. 6^a is a section of the smoke-box and dome at right angles to the line 4—4 in Fig. 2; Fig. 7 is a plan of the 35 water-dome-section; Fig. 8 is an edge view of the same; Fig. 9 is a plan of the steam-dome-section, and Fig. 10 an edge view of the same.

The firebox section is shown with a circular water-leg *a* and a crown-plate *b*, which plate is provided with a central hub *c* and perforated with a series (shown as six in number) of vertical flues or smoke-passages *d*. The outer edge of the crown-plate is in continuous 40 connection with the top of the circular waterleg, and the smoke-passages *d* extend through the crown-plate around the central hub or water-outlet *c*. This section rests upon an ash-box *p* having the usual 45 grate *q*, and the water-leg is perforated at one side with opening *a'* having the fire-door *a²*.

An open water communication exists between the central hub and the water-leg, through the body of the plate around the 55 several flues *d*. Between the flues hollow brackets *e* are extended from the plate to the water-leg, as shown in Figs. 5 and 6, being in open communication with both, so as to greatly increase the area of the passages 60 through which the water moves as it becomes heated.

A disk-section *f* having a central hub *c'* is shown superposed upon the hub of the crown-plate and connected thereto by a central nipple *g*. The disk is made with rounded periphery as shown in Fig. 4, and of suitable diameter to extend wholly over the flues *d* so as to deflect the smoke rising through the same laterally, as shown by the arrows *x*. 70

A flat plate-section *h* is shown above the disk *f*, with its central hub *c²* attached to the hub of the disk by a nipple *g*, and having flues *d'* similar to the flues *d* in the crown-plate *b*. A casing-plate *i* encircles the space 75 between the crown-plate and the flat section *h* and is provided with a cleaning-out door *f'*.

The several hubs are made of suitable length to form a sufficient space above and below the hollow disk *f* to permit the movement of the smoke and gases from the flues in the crown-plate to the flues in the plate *h*, as indicated by the arrows *x*. A dome-section *k* or *k'* (adapted respectively for a steam and a hot water boiler) is attached to the 80 hub of the plate-section *h* by a hub *c³*, the steam dome-section differing from the water-dome-section in having a greater height, and in practice having only a single outlet-pipe *l*, while the water-section is provided 85 with two pipes *l'* for inlet and outlet respectively. The section *k* is shown in full lines in Figs. 9 and 10, and the section *k'* in dotted lines in Figs. 7 and 8.

The outlet-pipe *l* may be placed in the center of the dome, as shown in Fig. 4, but is preferably placed near the front edge of the same, as shown in Figs. 9 and 10, to avoid the spray which rises from the current of liquid ascending in the hub *c³*. In Figs. 9 and 10, a baffle-plate *l²* is extended partly across the interior of the section between the central hub and the outlet-pipe which prevents the direct movement of any fluid from the 95 100

rising current to the outlet-pipe and thus secures the delivery of drier steam. The hubs of the plate-section *h* and of the dome-section are proportioned to form a smoke-chamber *r'* between such sections for the lateral passage of the smoke from the flues *d'*. The periphery of the smoke-chamber is inclosed by a casing *r* provided with a cleaning-out door *s*. The casing has a smoke-box *o* upon the side opposite to the door *s*, and is provided with a pipe-collar *p'* and with a check-damper *q'*.

A deflector *h'* which is preferably of conical form, and embracing about one-half a circle, 15 is inserted in the smoke-chamber *r'* just outside the flues *d'* upon the side next to the smoke-box *o*, as shown in Fig. 2, so as to inclose the flues *d'* upon their side and prevent the direct passage of the gases to the smoke-box. Such deflector causes the gases from 20 this portion of the flues *d'* to take a circuitous path in moving to the smoke-outlet, as is indicated by the arrows *x'* in Fig. 4.

In a steam heating boiler, the return pipe 25 *m* for condensed water is connected with the bottom of the water-leg *a*. A circulating-pipe *n* is also connected with the bottom of the water-leg and with the dome-section to permit the chilled liquid to pass downwardly 30 as the heated liquid rises in the boiler. The pipe *n* furnishes a means for connecting the pressure-pipe of a diaphragm damper-regulator with the boiler in such a manner that only water pressure will be transmitted normally 35 to the diaphragm, and the access of steam to the diaphragm (which will be injurious thereto) will be prevented, and whereby any accidental breaking of the diaphragm will discharge only a few inches of water from 40 the boiler, leaving the sections suitably filled with water to prevent burning. These results are attained by inserting the pressure supply-pipe *s'* for the damper-regulator *t* into 45 a fitting *u* upon the top of the circulating-pipe, and extending the same downward into the circulating-pipe, for only a few inches below the normal water-line *w* in the boiler, but not to the level of the under side of the dome-section. By this construction an accidental 50 breaking of the diaphragm will permit water to be blown partly from the dome-section to the level of the line *w'*, but not wholly emptying the same, thus leaving the water in all of the other sections and a sufficient amount in 55 the dome-section to prevent burning.

From the above description it will be seen that the boiler is composed of castings which are united at the center only, and which provide a tortuous passage for the gases in their 60 movement to the smoke-outlet, and a large amount of heating surface in proportion to the size of the sections.

Having thus set forth the nature of the invention what is claimed herein is:

1. In a boiler having horizontal sections 65 with central hub for water connection, the combination, with a flat disk-section having casing extended around the same and provided with cleaning-out door, of a firebox section fitted to such casing below the same 70 with a series of flues around the central hub discharging the gases beneath such disk-section, a superposed flat section with a series of flues around the central hub, a dome-section having a bottom water connection with 75 the superposed flat section, the two sections being separated by space for the lateral passage of the smoke, a casing surrounding the margin of such smoke-space with smoke-box having pipe-collar thereon, and a deflector 80 inclosing the flues through the superposed section upon the side next to such smoke-box.

2. In a steam heating boiler having horizontal sections, the combination, with a firebox section having an annular water-leg, a steam-dome section, and intermediate sections all joined by central water connections, the dome-section having an outlet and the bottom of the water-leg having an inlet, with 85 a circulating pipe connecting the same, and a diaphragm damper-regulator having its pressure pipe extended into the top of the said circulating pipe several inches below the water level of the boiler, whereby the water 90 pressure is transmitted to the diaphragm without access of steam, and the breaking of the diaphragm discharges only a few inches of water from the boiler.

3. In a boiler having horizontal sections 100 with central hub for water connection, the combination, with a flat disk-section having casing extended around the same and provided with cleaning-out door, of a firebox section fitted to such casing below the same 105 with a series of flues around the central hub discharging the gases beneath such disk-section, a superposed flat section with a series of flues around the central hub, a dome-section having a bottom water connection 110 therewith, the two sections being separated by space for the lateral passage of the smoke, a casing surrounding the margin of such smoke-space with smoke-box upon one side having pipe-collar thereon, a deflector between such outlet-box and the nearest smoke-flues in the flat section, and a cleaning-out door upon the said casing opposite to the smoke-box, the whole arranged and operated substantially as set forth.

4. In a boiler having horizontal sections with central hub for water connection, the combination, with a firebox section having an annular water-leg with hollow crown-plate having smoke passages around the central hub, a superposed flat section having similar flues around its central hub, and a disk-section intermediate to said sections

with smoke space between the disk and the flues above and below the same, and around the margin of the disk for the passage of the smoke, and dome-sections fitted interchangeably to the hub upon the top of the flat superposed section.

5 In testimony whereof I have hereunto set

my hand in the presence of two subscribing witnesses.

WILLIAM M. MACKAY.
